UNITED STATES PATENT OFFICE.

ALBERT HENRY MIDGLEY, OF UXBRIDGE, ENGLAND, ASSIGNOR TO MIDGLEY CAR LIGHTING COMPANY, LIMITED, OF LONDON, ENGLAND.

ELECTRIC STARTER FOR INTERNAL-COMBUSTION ENGINES.

Application filed April 3, 1922. Serial No. 549,330.

To all whom it may concern:

Be it known that I, ALBERT HENRY MIDGLEY, a subject of the King of Great Britain and Ireland, and residing at "Fairfield,"

5 Harefield Road, Uxbridge, in the county of Middlesex, England, have invented certain new and useful Improvements in Electric Starters for Internal-Combustion Engines, of which the following is a specification.

10 This invention relates to electric starters for internal combustion engines with particular reference to those employed in connection with motor or other vehicles and of the kind in which one or more of the 15 brushes of the starting motor is or are used as the starting switch.

The object of the present invention is to devise improved means for controlling the movable brush or brushes whereby the 20 operation of the apparatus may be made more certain and effective in practice so that there will be no danger of the position of the brushes not corresponding with that of the starting switch or other operative member 25 by which the brushes will be controlled.

With these and other objects in view the invention consists in the novel arrangements and combinations hereinafter described and illustrated and pointed out in the append- 30 ant claims.

The accompanying drawings illustrate one mode of carrying out the invention.

Figure 1 is an elevation of one form of 35 starter and brush gear in accordance with the invention, the same being removed from the casing and the latter indicated in broken lines.

Figure 2 is a view taken in the reverse 40 direction and showing the starter brushes in the normal non-starting position the position of the casing being shown in broken lines.

Figure 3 is a sectional view taken on the line 3—3 of Fig. 1 showing the manner of 45 arranging the starter and brush gear in the casing.

Figure 4 is a detail section taken in the 50 plane of one of the screws securing the brush holder supporting ring in the casing.

55 In carrying my invention into effect in one convenient manner I provide the usual battery for supplying current for the lighting and ignition systems and the usual switch-board for controlling the lighting

and ignition circuits neither the battery nor 55 the switch-board being shewn.

The switch-board is also provided with a lever or other operative device connected to one end of a Bowden wire a or like flexible controlling member adapted to control the 60 starting circuit in a manner hereinafter described.

The starter illustrated in the drawings comprises a casing a' Fig. 3, on the outside of which is mounted a bracket b through a 65 flange b' of which passes an adjustable screw b^2 adapted to accommodate the Bowden wire a , the end of which is connected to a member e' secured to a lug upon a ring or like rotary member c mounted within the 70 casing a' .

In the particular form shewn the starter comprises four brush-holders d d' , two of which (namely, those marked d') are movable for the purpose of enabling the brushes 75 to be moved out of or into contact with the commutator so that such movable brushes may be employed in known manner as the starting switch. The parts are held in place in the casing a' by means of the screws f 80 passing through slotted apertures in the ears f' of the ring f^2 which carries the brush holders, and behind which the ring c is mounted for rotation on the central boss g .

The movable brush-holders are provided 85 with arms or projections d^2 adapted to contact with pins or the like c' upon the arms c^2 of the ring c and between the flange b' on the member b and the member e' is a spring e of sufficient strength so as normally 90 to hold the ring c in such a position that the movable brush-holders d' are held against their controlling springs d^3 so that the brushes in such brush-holders are normally 95 out of contact with the commutator, the position of the parts being as shewn in Figure 2.

When it is required to bring the starter into operation the starting lever or switch is utilized to pull upon the Bowden wire a 100 thereby moving the ring c against the force exerted by the spring e in such a manner that the movable brushes are allowed to come into contact with the commutator segments thus completing the circuit and start- 105 ing the motor.

The lever or other operative device for actuating the Bowden wire control is pref-

erably also interlocked with the ignition switch so that the motor cannot be started until the ignition circuit has been inserted.

Having now described my invention what I claim as new and desire to secure by Letters Patent is:—

- 5 1. In an electric starter for internal combustion engines comprising a motor having a commutator and a movable brush in connection therewith to serve as the starting switch, means for controlling said movable brush comprising a brush-holder for said brush having an extension thereon, a ring having a pin adapted to contact with said extension, a spring controlling said ring so as normally to hold the brush away from the commutator segments and a Bowden wire for overcoming the force of said spring to allow the brush to contact with the commutator segments, substantially as described.
- 10 2. In an electric starter for internal combustion engines comprising a motor having a commutator and movable brushes in con-

nection therewith to serve as a starting switch, means for controlling the movable brushes comprising brush-holders for said movable brushes having extensions thereon, a rotary member having pins thereon adapted to contact with said extensions, a spring controlling said rotary member so as normally to hold the movable brushes out of contact with the commutator segments, a Bowden wire for rotating said rotary member against the action of said spring so as to move the pins on the rotary member out of contact with the extensions on the movable brush-holders and springs controlling said brush-holders to bring the brushes into contact with the commutator segments when the force of spring controlling said rotary member is overcome by the Bowden wire.

In testimony whereof I have signed my name to this specification.

ALBERT HENRY MIDGLEY.
